Primary Examiner — Derrick Holland(74) *Attorney, Agent, or Firm* — Reed Smith, LLP(57) **CLAIM**

The ornamental design for a multi-cable manager, as shown and described.

DESCRIPTION

FIG. 1 is a perspective view of a multi-cable manager showing my new design;

FIG. 2 is a first side view thereof;

FIG. 3 is a second side view thereof;

FIG. 4 is a third side view thereof;

FIG. 5 is a top plan view thereof; and,

FIG. 6 is a bottom plan view thereof.

The broken lines shown represent unclaimed subject matter and form no part of the claimed design.
